SELF-LOCKING THREADED DEVICE

Clarence W. Soldan, Baltimore, Md., assignor to
Crown Cork & Seal Company, Inc., Baltimore,
Md., a corporation of New York

Application October 25, 1944, Serial No. 560,221

26 Claims.

(Cl. 151—14)

The present invention relates to self-locking threaded devices of the type disclosed in the application of Hiram R. Harding, Serial No. 480,684, filed March 26, 1943, for Self-locking threaded elements.

An important object of the invention is to provide self-locking threaded elements of such construction that when they are used with companion threaded elements, neither element can move with respect to the other due to vibration.

Another object of the invention is to provide self-locking threaded elements of such design that they can be readily assembled and threaded into companion elements.

Other objects and advantages of the invention will be apparent from the following specification and accompanying drawings wherein:

Figure 1 is an elevation of a cap screw constructed in accordance with the present invention;

Figure 2 is a view showing the leading end of the Figure 1 cap screw in side elevation, a floating thread member included in the present invention being omitted from the view;

Figure 3 is an axial section on the line 3—3 of Figure 2;

Figure 4 is a transverse section on the line 4—4 of Figure 2;

Figure 5 is an end view of the cap screw of Figure 2, the view being taken from the right of Figure 2;

Figure 6 is a view showing the cap screw and floating thread member in side elevation and illustrating a companion threaded element in axial section;

Figure 6a is a transverse section on the line 6a—6a of Figure 6;

Figure 7 is a view similar to Figure 6 but showing the cap screw fully threaded into the companion threaded element;

Figure 7a is a transverse sectional view on the line 7a—7a of Figure 7;

Figure 8 is a view similar to Figure 6 but showing the cap screw being unthreaded from the companion element;

Figure 8a is a transverse section on the line 8a—8a of Figure 8;

Figure 9 is an end view of the leading end of the cap screw with the floating threaded member applied thereto in the position illustrated in Figure 6;

Figure 10 is a transverse sectional view on the line 10—10 of Figure 6;

Figure 11 is a greatly enlarged view showing an assembled floating thread member and cap screw,

the cap screw being indicated in dot and dash lines;

Figure 12 is a view of the floating thread member of Figure 11 as viewed from the direction indicated by the arrow a in Figure 11;

Figure 13 is a side view of the floating thread element viewed from the direction indicated by the arrow b of Figure 11;

Figure 14 is a radial sectional view of the floating thread member;

Figure 15 is a side elevation of a cap screw of modified form;

Figure 16 is a transverse section of the modified floating thread member shown in Figure 17, and

Figure 17 is a greatly enlarged view showing the modified cap screw of Figure 15 assembled with a modified form of floating thread member, the cap screw being indicated in dot and dash lines.

Referring to Figures 1 to 14, the numeral 1 designates a cap screw constructed in accordance with the present invention, the cap screw being provided with an American National coarse thread indicated at 2.

National Bureau of Standards Handbook H28, 25 entitled "Screw-Thread Standards for Federal Services—1942" specifies that the thread profile known previously as "United States Standard" shall be hereafter known as the "American National" thread.

As shown best in Figure 2, the leading end of the cap screw has a portion of the threads removed therefrom as indicated at 3, with the result that the thread of the cap screw begins at the point 4 which is spaced from the point at which

35 the thread would normally begin on such a cap screw. The length of thread 5 beginning at point 4 is of extremely short extent and terminates in a concave abutment 10 at an axially extending groove 6. Beyond groove 6, one helix of the thread 2 is entirely omitted and, instead, a helical groove 7 is formed in the cap screw, the groove 7 extending substantially 360° to enter the opposite side of the axially extending groove 6.

As is best shown in Figures 2 and 5, the axial groove 6 is substantially semi-circular in transverse section, the curvature or radius of the groove being of an outline hereinafter discussed. However, as shown in Figure 4, the maximum depth of the axial groove 6 along a line extending

45 diametrically of the screw, is the same as the depth of the helical groove 7. As shown in Figures 2 and 4, the groove 7 extends below the root or minor diameter 8 of the threads 2 to a distance substantially corresponding to the height to which the threads 2 extend above the root diam-

eter 9. The bottom wall 16 of the helical groove 7 is concentric with the axis of the cap screw, except as hereinafter described.

The helical groove 7 must be regarded as extending into axial groove 6 in that the end 10 of thread 5 on one wall of the axial groove forms an abutment at the leading end of the helical groove. Also, the end 11 of the thread 2 beginning opposite the wall of axial groove 6 forms the trailing end of helical groove 7 in that it forms an abutment at the trailing end of the helical groove.

As best shown in Figure 4, the helical groove 7 includes a restriction 20 in the form of a radial projection or enlargement on its bottom wall 16. The restriction 20 includes an outer or top surface 21 concentric with the axis of the cap screw which, in a .75" cap screw, for example, would extend approximately 25°. An incline 22 also forming part of the restriction joins the bottom or inner wall 16 of helical groove 7 to the surface 21 of the restriction. Inclined surface 22 is preferably formed by a radius based outside the cap screw so that the incline will be a relatively flat concave curve. It will be noted that the incline 22 forms the leading side of the restriction 20 and that the trailing side of the restriction is formed by the axial groove 6.

As best shown in Figure 4, the diameter on which the surface 21 of restriction 20 is formed is less than the root or minor diameter 9 of the threads 2. It will be noted from Figure 2 that the unthreaded portion 3 of the screw is of the same diameter as the root or minor diameter 9.

The helical band or floating thread element 25 shown in detail in Figures 11 to 14 is positioned in the helical groove 7. As illustrated in Figure 11, the band 25 extends for approximately 335°. Its outline in radial section is illustrated in Figure 14 from which it will be observed that the band includes a flat inner surface 26 and relatively short side walls 27. Outwardly of the side walls 27, the band is provided with a thread 28 of the same cross-sectional conformation as the threads 2 of the cap screw 1. While member 25 is of generally helical form, it is not of uniform diameter throughout its length. For example, as clearly indicated in Figure 11, both ends 29 and 30 are bent or deflected inwardly from a helix so that the innermost point of each end is closer to the diametrically opposed point on the surface 26 than is the case with any other two diametrically opposed points on the inner surface 26.

The member 25 is formed of spring steel to be bodily resilient, though it has sufficient rigidity to exert strong pressure against any effort to bend it inwardly from the normal form illustrated in Figure 11 and, when bent inwardly, will exert considerable force outwardly.

Figures 6 and 6a show the band 25 fitted in the helical groove of the cap screw 1, and it will be noted that the end 29 forms the leading end of the band while the opposite end 30 forms its trailing end. The diameter of the inner surface 26 of the member 25 is sufficiently larger than the diameter of the surface 16 of groove 7 that member 25 may move diametrically and circumferentially in the groove 7 when not within a companion threaded element. Because of this, the member 25 can be regarded as a floating thread on element 2 as referred to above. With regard to circumferential movement of member 25 in the groove 7, it will be clear from Figures 6a to 8a that member 25 can only move clockwise in these figures to such extent that its trailing end 30 will abut against the leading end 11 of the

threads 2 of the cap screw. When moved in the opposite direction, the leading end 29 of member 25 will come into abutment with the end 10 of the short length of thread 5. Before the trailing end 30 of member 25 can contact with the leading end 11 of the threads 2, it must move over the restriction 20.

For the purpose of setting forth the general form of a typical self-locking element of the present invention, it may be pointed out that a .75" American National coarse thread cap screw constructed in accordance with the present invention to have a Class 2 fit, will have the base wall 16 of its helical groove 7 formed on a radius of .249", while the surface 21 of restriction 20 will be formed on a radius of .285". In accordance with standards specified in said Handbook H28, the minor diameter of the screw 1, i. e., its diameter at the root 9 of the threads would be .6273".

It is to be noted that a .75" American National coarse thread cap screw designed to have a No. 2 fit with a female element may have the major diameter of its threads a minimum of .7372", i. e., a radius of .3686", as indicated in Figure 11 of the present application. The female or nut element to be used with such a screw would have the root or major diameter of its threads a minimum of .75". In other words, with a No. 2 fit, and with the screw of minimum tolerance major diameter, the companion elements would have a diametrical play of .0128".

The member 25 to be used with a .75" American National coarse-thread screw such as indicated by the numeral 1 would be of a radial thickness of .0929" as indicated in Figure 14. Figure 11 gives radial dimensions for a member 25 provided for use with such a .75" coarse threaded cap screw having a No. 2 fit. It will be noted from this figure that the member 25 is symmetrical in that the two halves thereof on opposite sides of the diametrically extending lines C-C are identical in configuration. More particularly, within each of the arcs G, which comprise the central portion of member 25 and extend for substantially 90° in each direction from the right-hand end of the line C-C in Figure 11, the member 25 has an outside radius of .3839" and an inside radius of .291". Then, throughout the arcs H extending for 44°, the outside radius is formed on a curvature of .367" centered on the lines G' which form the outer limits of the arcs G. From the lines H' defining the ends of the arcs H, the outside radius of member 25 is formed on a curvature of $\frac{3}{2}$ " based on each line H'. By reason of the above-described inward deflection of member 25 adjacent its ends, its inside radius adjacent each line H' will approximate .285", i. e., the radius of restriction 20 of screw 1. The purpose of this is hereinafter described.

As is clear from Figures 4 and 5, the axial groove 6 is curved in transverse section and Figure 11 shows the radius which may be used for this curvature. By having groove 6 concavely curved, instead of with straight side walls, it can be formed by a single milling operation. In any event, the end surfaces of the ends 29 and 30 of ring or band 25 will have a form to closely fit the surfaces 10 and 11 defined by groove 6.

Because of the changes in radii at the lines G' and H', these lines, in effect, comprise bending points of the member 25.

From the above, and from Figure 11, it will be noted that the member 25, throughout the

two arcs G, is normally of greater outside radius than the radius of the root or major diameter of a companion female threaded member to receive screw 1. That is, throughout the 180° of member 25 encompassed in the arcs G, member 25 is of a .3839" outside radius, whereas the root or major diameter of a companion female threaded member is of .375" radius. Figure 11 clearly indicates that member 25, when unrestricted, has an outside radius throughout the major portion of its length which is greater than the major radius of the threads of screw 1.

It will also be observed from Figure 11 that the member 25 might be described as a helix which is flattened along a line extending between its two ends, as is the case with the line C—C. Stated another way, member 25 may be described as a symmetrically distorted helix, or a helix having its ends bent inwardly.

The manner in which the floating thread member 25 of Figures 1 to 14 performs a locking function in cooperation with the screw 1 and a companion threaded member is as follows: Figures 6 and 6a show the threaded element 1 being initially threaded into a machine body or base 35 provided with American National coarse threads 36. As shown in Figure 6a, the screw 1, being right-handed, will rotate in the direction of the arrow of Figure 6a, thereby rotating and moving to the right as indicated by the bent arrow of Figure 6. Before the member 25 is engaged with the threads 36, its trailing portion 30 should be positioned in contact with the leading end 11 of the threads 2 as shown in Figs. 6, 6a, and 11, so that the end 30 will lie in the axial groove 6 and with its end surface in contact with surface 11. Although member 25 is normally oversized in outside dimension with respect to the threads 35, a threaded member 1 carrying the member 25 can be threaded into the threads 36 upon the application of sufficient force to the tool being used. Under these circumstances, the resiliency of the member 25 will enable it to contract somewhat. Generally speaking, this contraction will occur by inward springing of the member 25 throughout all of the portion thereof other than the end 30 and the portion adjacent that end which is lying upon the restriction 20 as indicated in Figure 11. This inward springing will cause end 29 to move slightly counter-clockwise in groove 7 as viewed in Figure 11 and may even result in bending end 29 outwardly, thereby increasing the tension exerted on threaded element 35.

Figures 7 and 7a show the cap screw 1 fully threaded into the element 35, and it will be observed that the member 25 still occupies the position relative to screw 1 which is illustrated in Figure 6a because threading rotation of screw 1 keeps shoulder 11 in contact with the end surface of end 30 of band 25.

The strong force exerted outwardly against the threads 36 by reason of the fact that member 25 is normally oversized with respect thereto throughout the greater portion of its length will prevent member 25 from having unthreading movement with respect to the threads 36. Hence, if screw 1 is to turn in the direction of the arrow designated "To unthread" in Figure 11, it must turn relative to the member 25. In other words, vibration cannot cause member 25 to turn with element 1 in an unthreading direction. In fact, member 25 and element 1 can only turn together in an unthreading direction under the conditions described below and involving the application of extremely strong turning force to the element 1.

Even extreme vibration will not cause member 1 to unthread with respect to the threads 35 because any unthreading rotation of screw 1 from the position shown in Figures 7, 7a, and 11 (and clockwise with respect to those figures) will simply cause the restriction 20 at the trailing end of groove 7 to move into closer contact or engagement with the surface 31 of member 25. Such movement would have the effect of bending the inwardly curved trailing end 30 outwardly from the position shown and this could not be accomplished by vibration alone.

If it is desired to remove the cap screw 1 from the element 35, a wrench of the usual form and size is applied to the cap screw and, upon the application of strong force to the wrench, the cap screw may be reversely rotated in the direction of the arrows of Figures 8 and 8a. The operation of the member 25 under these conditions is as follows: Because of its bodily resiliency and tendency to expand so that the greater portion of its length will be of larger outside radius than the diameter of the threads 36 of companion element 35, member 25 will be prevented from rotating in the element 35. However, with the proper force applied, the member 25 will bend adjacent its end portion 30 so that the restriction 20 will move beneath the surface 31. When the inner tip 32 bears upon the surface 20, the cap screw can then be turned to move the end 30 off restriction 20 so that the screw 1 will occupy the position with respect to member 25 illustrated in Figure 8a. In this position, the opposite end 29 of member 25 will lie in the axial groove 6 to abut against the surface 10 of the groove so that the member 25 must then unthread with element 1. While the oversized dimensions and resiliency of member 25 will still cause it to exert a strong drag against the threads 36 during unthreading rotation of the cap screw in the direction of the arrows of Figures 8 and 8a, the cap screw can be unthreaded with the application of proper force to the wrench.

Because of the fact that the member 25 of Figures 1 to 14 is of symmetrical form, it is immaterial which end of member 25 is positioned as the leading end 29 when it is placed upon a screw 1. This saves time in the assembly of the floating thread member upon screw 1.

The provision of an unthreaded area such as 3 at the end of a cap screw enables the floating thread member to be placed in the helical groove 7 when the member 25 is sprung open for assembly. Because of the force required to spring the floating thread member open, it is impossible for the member to fall from the element 1 or even be removed except by special tools. Therefore, member 25 is, in effect, a permanent part of the screw 1.

It will also be observed that because the restriction 20 is always closely adjacent the inwardly formed surface 31 at the trailing end 30 of member 25, there can be a minimum of turning movement of screw 1 with respect to member 25 under vibration. That is, the slightest movement of screw 1 in the direction of the arrow marked "To unthread" in Figure 11 must bring the restriction 20 into even closer contact with the inwardly curved surface 31. Therefore, whenever a screw has been moved to the desired position, it can have no play in either direction, i. e., it is firmly locked against further possibility of movement as soon as threading movement by the operator has stopped.

In order to enable the floating thread member

25 to be more readily applied to cap screw 1, it may be desirable to provide the surface 3 of cap screw 1 of Figures 1 to 14 with a notch 3' in advance of the lead-in end 4 of the thread as shown in dotted lines in Figure 5. By this arrangement, when one end of the floating thread member 25 is aligned with the longitudinal groove 6, the opposite end will be aligned with the notch 3'. This eliminates the necessity of spreading the member 25 too sharply during assembly with the cap screw.

It has been found that an important reason why a floating threaded member such as disclosed herein and in said Harding application resists movement from a locked position such as shown, for example, in Figure 11, is the following: when an unthreading tendency is initiated, either by vibration or by intent of an operator, the resultant movement of a locking end such as 31 with respect to a restriction such as 20 imparts a force to the member 25 whereby the latter tends to straighten out throughout its entire length. As a result, a tremendous outward and radial pressure is applied by the member 25 to the threads of the companion element 35. This force is greatly augmented throughout the portions of member 25 which have a different, viz., larger, radius than that of the female element 35, as is the case with the portions of member 25 embraced by the arcs G in Figure 11.

I have found that the force exerted by the portions within the arcs G is so great that the size of the member 25 can be reduced according to various procedures hereinafter discussed, and that the resistance to unthreading movement will still be so high that it will be adequate to meet conditions faced in most installations. At the same time, the modifications hereinafter discussed have certain advantages such as (1) ease of insertion into a companion threaded element, and (2) easier unthreading movement after they have been released from a locked position such as shown in Figure 11.

In considering the modifications made in accordance with the principle stated above, it should be borne in mind that, throughout the foregoing description of the device of Figures 1 to 14, the floating thread member 25 has been described as having portions of its length of an outside diameter which is greater than the outside or major diameter of cap screw 1. It has also been pointed out that when member 25 is not within a female threaded element 35, the outside diameter of portions of member 25 is normally larger than the root or major diameter of a female threaded element 35. In short, the floating threaded element 25 of Figures 1 to 14 as hereinbefore described may be termed "oversized" in that portions thereof normally have an outside diameter which is larger than the major diameters of the threaded elements 1 and 35. Obviously, the portions of member 25 which are oversized in outside diameter are also oversized with respect to pitch diameter.

In connection with the above use of the term "pitch diameter," reference is made to the definition of the pitch diameter of a straight screw thread which appears on page 2 of the above-mentioned Handbook H28, which definition reads as follows: "Pitch diameter—On a straight screw thread, the diameter of an imaginary cylinder, the surface of which would pass through the threads at such points as to make equal the width of the threads and the width of the spaces cut by the surface of the cylinder."

With the above definition in mind, the character P in Figure 11 designates a point on the pitch diameter of the cap screw 1 as well as the companion threaded element or nut 35. The character P25 in Figure 11 designates a point on the pitch diameter of the portion of floating threaded element 25 which is within an arc G and, therefore, has both a larger outside diameter (or radius) and a larger pitch diameter than that indicated by P. It will be observed that since point P25 is spaced a greater distance from the axis of cap screw 1 than point P, the pitch diameter (or radius) of the portion of member 25 within arc G is larger than the pitch diameter or radius of the cap screw 1 and element 35.

It also will be observed that, according to the above definition, a thread may be truncated in section, and thereby have a broader crest, without its pitch diameter being reduced.

I have found that in numerous instances it is only necessary that the pitch diameter of portions of member 25 be larger than the pitch diameter of screw 1 and female threaded element 35, and that so long as this relationship is retained, the outside diameter of member 25 may be reduced. The dotted lines 25a superimposed on the floating thread member 25 of Figures 11 and 14 indicate how this member might be of smaller outside diameter so long as the pitch diameter indicated by P25 of portions thereof is greater than the pitch diameter P of elements 1 and 35.

It will be observed that making the line 25a the outer perimeter of member 25 simply means that the depth of the thread on 25 is decreased and that no other dimension of member 25 is thereby changed. In other words the portions of the tapered side walls of member 25 shown below line 25a in Figure 14 will still bear on the female thread of element 35 with the same force such portions exert if the member 25 has a thread of standard depth.

With the outside diameter of the floating thread member 25 reduced to conform to line 25a as described above, that is, if throughout its perimeter, member 25 is smaller than the major diameter of either screw 1 or element 35, an adequate locking effect will still be obtained if portions of member 25 have their pitch diameter (or radius) larger than the pitch diameter of elements 1 and 35. A member 25 formed in this manner has the advantage that it can be more readily threaded into a female threaded element 35. Nevertheless, as indicated above, its tapered side walls embraced within the arcs G in Figure 11 include entirely adequate surface to exert and maintain the necessary pressure upon the opposed tapered walls of the thread of female element 35 when member 25 has a straightening-out tendency applied thereto as hereinbefore explained.

Another way in which the "oversized" floating thread member 25 of Figures 1 to 14 can be reduced in outside diameter or radius is by reducing its inside diameter or radius and, at the same time, maintaining its section substantially the same as shown in solid lines in Figure 14. A member 25 having the last-mentioned characteristic can be regarded as an "undersized" floating thread member. As an example of the arrangement just mentioned, the portion of member 25 of Figure 11 within the arcs G, could have its inside radius throughout those arcs reduced from .291" (as illustrated in Figure 11) to .281". If this is done, and the section of the member 25 is maintained at the dimensions shown in Figure

14, the outside radius throughout the arcs G will be approximately .373". Therefore, the greatest outside diameter (along lines G'-G' in Figure 11) will be approximately .746" instead of .766".

The "oversized" floating thread member 25 disclosed in Figures 1 to 14, i. e., the form where- 25 in the outside radius of the member 25 throughout the major portion of its length, is greater than the outside radius of the threads of screw 1 and the outer perimeter and section of member 25 is as indicated in solid lines in Figures 11 and 14, is advantageous when the member 25 is formed of a metal which is relatively soft as compared to 1065 spring steel. However, in the event 15 that it is desired to form the member 25 of a metal having a hardness comparable to that 20 1065 spring steel, or even greater hardness, it is preferable to have the outside diameter of the member 25, throughout the length of the washer, less than the outside diameter of the screw as 25 above described. Also, in order to meet actual working conditions, it is frequently desirable to use an undersized washer because of the following circumstances. As has been hereinbefore 30 stated, a .75" American National coarse thread cap screw designed to have a Class 2 fit with a female element is finished to make the minimum major or outside diameter of its threads .7372". However, the maximum outside or major diameter of the cap screw threads which is permitted is .75". On the other hand, the female element to be used with such a screw may have a minimum thread base or major diameter approximating .750 inch. If a screw of maximum diameter is used with a floating thread member of the oversized type, an extremely tight fit with the female element will result. Therefore, it is frequently desirable to use a floating thread member of the undersized type. However, in some situations, for example, when it is assured that there will be a diametric play of .013 inch between the screw and the female element, an oversized floating thread member is entirely practicable.

It may be stated at this point that the matter of whether an undersized or oversized floating thread member is used does not affect the locking characteristics of the member for the same reasons as have been stated above in connection with the use of a member having its outside diameter reduced to the line 25a in Figures 11 and 14, but its pitch diameter and inside radii kept the same as illustrated in Figure 11. That is, when any unthreading tendency is applied, the floating thread member tends to straighten out, thereby exerting force against the female member.

An advantage of having the washer undersized is that once it has been moved to the unlocked position, it can be readily unthreaded because it exerts no marked drag upon the threads of the companion element.

Figures 15 to 17 disclose an undersized floating thread member of a third type. In addition, the structure shown in Figures 15 to 17 includes a non-symmetrical floating thread member and also may have a straight trailing end instead of a curved trailing end as indicated at 30 in the form of Figures 1 to 14. However, the structure hereinafter described in connection with Figures 15 to 17 has the characteristic common to the form of Figures 1 to 14 of having the floating thread member provided with a restriction engaging portion at its trailing end and also hav-

ing the helical groove of the cap screw provided with a restriction at its trailing end.

Referring to Figure 15, the cap screw 50 illustrated therein has its leading end formed in a manner generally similar to that of the form hereinbefore described, except that the axial groove 51 has a flat surface 52 extending parallel to a diameter of the cap screw. Also, the inner end 53 of groove 51 may be rounded. A groove 10 of this conformation can be formed by cutting a single milling operation.

The dimensions of the cap screw 50 are herein- 15 after set forth in connection with the description of the floating threaded member to be used therewith.

Figure 16 is a cross-sectional view of the floating thread member 54 designed for use with cap screw 50, the dimensions being those intended for use with a .75" American National coarse thread cap screw designed to have a Class 2 fit with a female element. As shown in Figure 16, member 54 would have a thickness of .083" thereby being narrower than the width of the helical groove 55, which is .1". The inclined or threaded portion of member 54 has its walls of the same tapered conformation as a thread of the threaded element with which it is to be used. The width of the flat outer portion or crest would be .018". Therefore, thread member 54 is truncated to have a different width of crest from a standard thread section, which latter would be .0125".

Figure 17 shows the floating thread member 54 of Figures 15 to 17 mounted upon a cap screw 50, the cap screw being illustrated in dot and dash lines. The base wall or inner wall 55 of helical groove 56 of cap screw 50 would be .25" in radius throughout the larger portion of its length. This groove would be a true helix as is the case with the corresponding groove of Figures 1 to 14. At its leading end 57, helical groove 56 would merge into the flat inner wall 52 of the axial groove 51, the latter groove being positioned $\frac{1}{4}$ " from the axis of the cap screw and having a width of $\frac{1}{16}$ ". The trailing end 58 of helical groove 56 is provided with a restriction 59 formed on a radius of .281", this restriction terminating at its trailing end at the flat inner wall of the axial groove 51. The leading side of restriction 59 includes an inclined wall 60 which blends into the .25" radius of the major portion of the base wall 55 of helical groove 56.

Figure 17 shows the flat trailing end portion 61 of floating thread member 54 positioned in the axial groove 51 of the cap screw, as would be the case when the cap screw is being threaded into a female element or is in locked position therein. Member 54 has the tip of its flat or locking end 61 positioned $\frac{1}{4}$ " from the tip of the leading end 62 and throughout an arc extending approximately 110° therefrom, and indicated by the arcuate line K, the inside radius of member 54 would be $1\frac{1}{4}$ " or .266". Since, as stated above, the radial thickness of member 54 is .087", its outside radius throughout arc K would be .353". From the radial line K' designating the end of arc K to line L' positioned at the beginning of the flat portion 61, the inside radius of member 54 is $\frac{1}{2}$ " or .281". Therefore, the outside radius of the arcuate portion designated by the line L is .368".

Because the maximum major diameter of a $\frac{3}{4}$ " American National coarse thread cap screw designed for a Class 2 fit is .75", or .375" radius, 75 whereas the portion of member 54 indicated by

arc K has an outside radius of only .353", it will be observed that this portion of member 54 is of smaller radius than the outside or major radius of the cap screw on which it is to be used. With regard to the remaining curved portion of member 54, i. e., that portion indicated by the arc L, this has an outside radius of .368" and, therefore, is only slightly undersized. However, as shown in Figure 17, the diameter of member 54 taken along a line passing through its leading end 60 is approximately .721. Since this diameter is a maximum diameter it will be clear that the maximum outside diameter of member 54 under normal conditions will be less than the maximum major diameter of .75" of the cap screw under discussion. The dimension between the flat inside surface 61a of tip 61 and the diametrically opposite point of threaded member 54 will be .531", as shown in Figure 17.

It will be observed that the straight trailing end 61 of member 54 comprises an inwardly deflected portion, as well as a portion bent inwardly out of the helix, just as is true of the corresponding curved end portion of the floating thread members of Figures 1 to 14.

With the device of Figs. 15 to 17 in the locked position indicated in Figure 17, i. e., with the flat surface at its trailing end 61 bearing against flat surface 52 and the tip of its trailing end against the wall 65 of groove 51, unthreading movement would be in the direction of the arrow A of Figure 17. Any force tending to rotate cap screw 50 in that direction, whether the force be applied by an operator or by vibration, will immediately cause the flat surface 52 of an axial groove 51 to exert an outward force at B in Figure 17 and in the direction of the arrow B, thereby urging and wedging the locking and trailing end of the floating thread member 54 against the threads of the female element. At the same time, because restriction 59 is bearing on the inner surface of member 54, the restriction 59 will move even more closely against the inner surface of the member 54 to apply a pressure acting to bend the locking member outwardly. As a result of these forces which act instantly upon any unthreading movement of the cap screw, back-lash and the possibility of unthreading by vibration are eliminated.

It is also to be noted that when the above forces are applied, a straightening out tendency is applied to the entire member 54 as has been pointed out above in connection with the other forms disclosed herein. Therefore, member 54 will be urged outwardly against the threads of the female element.

However, upon the application of suitable force to the cap screw, the restriction 59 can be moved in the direction of the arrow A and beneath the flat portion 61 of member 54, the member being of spring steel to permit this bending and so that it will then return to its normal shape.

Aside from the manner in which the device shown in Figs. 15 and 17 entirely prevents back-lash and immediately resists threading movement, it has certain advantages in manufacture. One such advantage arises from the fact that the points of the locking ring on which manufacturing tolerances must be closely observed are all within a small area of the locking ring. These tolerances involve only the length of the flat portion 61, and the extent to which it is offset with respect to the adjacent curved portion of the member. These tolerances are not difficult to maintain. It will be noted that the distance between the two ends of the member 54, or, stated

another way, the length of member 54 measured in a circumferential direction, is not highly critical. The fact that a critical tolerance need not be maintained at this point is advantageous because such a tolerance would be difficult to maintain. Also, in the manufacture of the cap screw, the critical tolerances are only those within the area occupied by axially extending groove 51 and restriction 59. These tolerances can readily be controlled during manufacture.

The devices of the present invention obviously require no special tools to operate them to locked position or to assist in unlocking. In addition, there are no parts which can deteriorate, as occurs with locking devices formed of compressible material and, in use, the floating thread is entirely enclosed so that it cannot be tampered with. The floating thread members are also of such design that they cannot become broken during operation and cannot mar the threads of a companion element.

It will be understood that the dimensions of the .75" cap screws of the present invention set forth herein are merely to disclose the dimensions used in an element of a given size and torque required and that the invention is applicable to threaded elements of all sizes. Furthermore, the dimensions stated for the .75" cap screws under discussion may be varied for even a screw of such size according to the conditions under which the invention is to be used.

It will be clear that the invention is applicable to threaded elements of numerous types other than cap screws.

The terminology used in the specification is for the purpose of description, the scope of the invention being indicated in the claims.

I claim:

1. In a self-locking threaded device, a threaded element including a helical groove having a pitch substantially corresponding to the pitch of its threads, a substantially helical member mounted in the groove, at least a portion of said member normally being of a different radius from the radius of the thread of said element, said helical member being bodily resilient to bend and thereby conform to a companion threaded element engaged by said first element, but being sufficiently rigid that it will exert radial pressure upon the companion element to resist turning movement with respect to the latter, and coacting means respectively carried by said threaded element at the trailing end of the helical groove and at the trailing end of said helical member whereby the latter will be more strongly urged into contact with a companion threaded element upon unthreading movement of said first threaded element with respect to a companion threaded element.

2. A self-locking threaded device of the character described in claim 1 wherein said helical member is symmetrical.

3. A self-locking threaded device of the character described in claim 1 wherein the greatest radius of said helical member is less than the major radius of said threaded element.

4. A self-locking threaded device of the character described in claim 1 wherein the greatest radius of said helical member is greater than the major radius of said threaded element.

5. In a self-locking threaded device, a threaded element including a helical groove having a pitch substantially corresponding to the pitch of its threads, a substantially helical member mounted in the groove, a thread on said helical member

of different radial section than the thread of said elements, at least a portion of said member normally being of a different radius from the radius of the thread of said element, said helical member being bodily resilient to bend and thereby conform to a companion threaded element engaged by said first element, but being sufficiently rigid that it will exert radial pressure upon the companion element to resist turning movement with respect to the latter, and coacting means respectively provided at one end of the groove and at the corresponding end of said helical member adapted to engage upon unthreading of said first element with respect to a companion threaded element.

6. In a self-locking threaded device, a threaded element including a helical groove having a pitch substantially corresponding to the pitch of its threads, the groove having a restriction at its trailing end, a substantially helical member mounted in the groove, at least a portion of said member normally having a pitch diameter different from the pitch diameter of the thread of said element, said member being bodily resilient to bend and thereby conform to a companion threaded element engaged by said first element, but being sufficiently rigid that it will exert radial pressure upon the companion element to strongly resist turning movement with respect to the latter, said helical member being provided with an inwardly deflected portion at its trailing end to engage the restriction in the groove of said first element upon unthreading of said first element with respect to a companion threaded element.

7. In a self-locking threaded device a threaded element including a helical groove having a pitch substantially corresponding to the pitch of its threads, the groove having a restriction therein, a substantially helical member mounted in the groove, at least a portion of said member normally having a pitch diameter different from the pitch diameter of the thread of said element, said member being bodily resilient to bend and thereby conform to a companion threaded element engaged by said first element, but being sufficiently rigid that it will exert radial pressure upon the companion element to strongly resist turning movement with respect to the latter, said groove restriction being adapted to engage said member upon unthreading of said first element with respect to a companion threaded element, the greatest diameter of said helical member being less than the major diameter of said first-named threaded element.

8. In a self-locking threaded device, a threaded element including a helical groove having a pitch substantially corresponding to the pitch of its threads, the groove having a restriction therein, a substantially helical member mounted in the groove, said member including end portions bent inwardly out of the helix, said groove restriction being adapted to engage one of said bent portions upon unthreading of said element with respect to a companion threaded element.

9. In a self-locking threaded device, a threaded element including a helical groove having a pitch substantially corresponding to the pitch of its threads, the groove having an outwardly projecting restriction therein at its trailing end, a substantially helical member mounted in the groove, said member having an inwardly deflected portion on its trailing end adapted to engage the restriction upon unthreading of said element with respect to a companion threaded element.

10. In a self-locking threaded device, a threaded element including a helical groove having a pitch substantially corresponding to the pitch of its threads, the trailing end of said groove terminating in a substantially radially extending shoulder, a radial projection adjacent the trailing end of said groove, a helical member mounted in the groove and of less length than the latter, said member including a portion at its trailing end adapted to engage the groove restriction upon unthreading movement of the threaded element with respect to a companion threaded element.

11. In a self-locking threaded device, a threaded element including a helical groove having a pitch substantially corresponding to the pitch of its threads, the trailing end of the groove terminating in a substantially radially extending shoulder, a radial projection adjacent the trailing end of said groove, a helical member mounted in said groove and of a length less than the length of the groove, said member having its trailing end arranged to be engaged by the restriction upon unthreading of said element with respect to a companion threaded element, so that said end of the member will be forced against the companion threaded element.

12. In a self-locking threaded device, a threaded element including a helical groove having a pitch substantially corresponding to the pitch of its threads, the groove having a restriction therein, a symmetrical substantially helical member mounted in the groove, said member extending through approximately 335° and having an outside radius throughout substantially 180° which is greater than the greatest opposed diameter of a companion threaded element so that said member will not turn with respect to a companion threaded element upon vibration, and coacting means in the groove and upon the remaining portion of the length of said member adapted to engage and further urge said member into locking relation with a companion threaded element upon unthreading movement of said grooved element with respect to the companion threaded element.

13. In a self-locking threaded device, a threaded element including a helical groove having a pitch substantially corresponding to the pitch of its threads, the groove having a restriction therein, a symmetrical substantially helical member mounted in the groove, said member extending through approximately 335° and having an outside radius throughout substantially 180° which is greater than the greatest opposed radius of a companion threaded element, the remainder of the length of said member having a radius less than the greatest opposed diameter of a companion threaded element, and coacting enlargements on the last mentioned portion of said member and in the groove adapted to come into contact upon unthreading movement of said threaded element with respect to a companion threaded element to urge said portion of small radius into contact with the companion element.

14. A self-locking screw having within its threads a helical groove of a pitch substantially corresponding to the pitch of its threads, a substantially helical member mounted in said groove, said helical member being of less length than the groove and being freely movable lengthwise of the groove, said helical member having portions curved on radii of different lengths, the radius of curvature of the central portion of said member providing an arc substantially concentric in

respect to the screw and the radius of curvature of the end portions of said member providing an arc eccentric in respect to the screw.

15. A self-locking screw having within its threads a helical groove of a pitch substantially corresponding to the pitch of its threads, a substantially helical member mounted in said groove, said helical member being of less length than the groove and being freely movable lengthwise of the groove, said helical member having portions curved on radii of different lengths, the radius of curvature of the central portion of said member providing an arc substantially concentric in respect to the screw and the radius of curvature of the end portions of said member providing an arc eccentric in respect to the screw, and the outside diameter of an appreciable portion of said member being sufficiently greater than the outside diameter of the threads of said screw to take up all play between the screw and a companion female element, such as a nut.

16. In a self-locking threaded device, a threaded element including a helical groove having a pitch substantially corresponding to the pitch of its threads, the groove extending through substantially 360° , a radial enlargement adjacent but spaced from the trailing end of the groove, both ends of the groove terminating in substantially radially extending shoulders, a substantially helical and bodily resilient member mounted in the groove, said member extending through approximately 335° and having an outside radius throughout substantially 180° and in its central portion which is normally greater than the greatest opposed diameter of a companion threaded element so that said member will not turn with respect to a companion threaded element upon vibration, the trailing end of said member being adapted to abut against the trailing end of said groove during threading movement of said grooved element with respect to a companion threaded element, said member being provided with inwardly curved resilient portions at both ends thereof, the restriction in the groove being adapted to move beneath the inwardly curved portion at the trailing end of said member upon unthreading movement with respect to a companion element and to thereby force said trailing end outwardly into closer engagement with the companion element, said trailing end portion being adapted to move over the groove restriction upon the application of sufficient force to said grooved element whereby the inwardly curved portion at the leading end of said member will contact with the radial shoulder at the leading end of the groove to force said member to unthread with said grooved element.

17. In a self-locking threaded device, a threaded element including a helical groove having a pitch substantially corresponding to the pitch of its threads, said element including a flat surface at one end of the groove lying in a plane substantially parallel to a diameter of the threaded element, a substantially helical member mounted in the groove, said member including an inwardly deflected end portion to bear upon the flat grooved surface in locked position with respect to a companion threaded element.

18. A self-locking threaded device of the character described in claim 17 wherein the inwardly deflected portion of said helical member is straight.

19. In a self-locking threaded device, a threaded element including a helical groove having a pitch substantially corresponding to the pitch of its

threads, said element including a flat surface at the trailing end of the groove lying in a plane substantially parallel to a diameter of the threaded element, a substantially helical member mounted in the groove, said member including an inwardly deflected end portion to bear upon the flat grooved surface in locked position with respect to a companion threaded element.

20. A self-locking threaded device of the character described in claim 19 wherein the inwardly deflected portion of said helical member is straight.

21. In a self-locking threaded device, a threaded element including a helical groove having a pitch substantially corresponding to the pitch of its threads, said element including a flat surface at one end of the groove lying in a plane substantially parallel to a diameter of the threaded element, the groove having a restriction therein adjacent the flat surface, a substantially helical member mounted in the groove, said member including an end portion bent out of the helix to lie straight and bear upon the flat grooved surface in locked position with respect to a companion threaded element.

22. In a self-locking threaded device, a threaded element including a helical groove having a pitch substantially corresponding to the pitch of its threads, said element including a flat surface at the trailing end of the helical groove lying in a plane substantially parallel to a diameter of the threaded element, the groove having a restriction therein adjacent the flat surface, a substantially helical member mounted in the groove, said member including an end portion bent out of the helix to lie straight and bear upon the flat grooved surface in locked position with respect to a companion threaded element.

23. In a self-locking threaded device, a threaded element including a helical groove having a pitch substantially corresponding to the pitch of its threads, a substantially helical member mounted in the groove, at least a portion of said member normally being of different radius from the radius of the thread of said element, said helical member being bodily resilient to bend and thereby conform to a companion threaded element engaged by said first element, but being sufficiently rigid that it will exert radial pressure upon the companion element to resist turning movement with respect to the latter, and coacting means carried by said threaded element and said helical member whereby the latter will be more strongly urged into contact with a companion threaded element upon unthreading of said first threaded element with respect to a companion threaded element, said helical member having a thread of less than standard depth, but which is otherwise of the same transverse section as the thread of said first named threaded element.

24. A self-locking threaded device of the character described in claim 8 wherein said helical member is provided with a thread of the same section as that of said threaded element and the greatest radius of said helical member is less than the major radius of said threaded element.

25. A self-locking threaded device of the character described in claim 8 wherein said helical member is provided with a thread which is truncated in radial section.

26. A self-locking threaded device of the character described in claim 5 wherein said helical member is provided with a thread which is truncated in radial section.

CLARENCE W. SOLDAN.
